Patented Dec. 14, 1915.

UNITED STATES PATENT OFFICE.

ISRAEL C. ORSWELL, OF HYDE PARK, MASSACHUSETTS, ASSIGNOR TO ORSWELL IGNITER COMPANY, OF BOSTON, MASSACHUSETTS, A CORPORATION OF MAINE.

SPARKING PLUG.

1,164,113.

Specification of Letters Patent. Patented Dec. 14, 1915.

Application filed April 26, 1907. Serial No. 370,347.

To all whom it may concern:

Be it known that I, ISRAEL C. ORSWELL, a citizen of the United States, residing at Hyde Park, in the county of Norfolk and 5 State of Massachusetts, have invented an Improvement in Sparking Plugs, of which the following description, in connection with the accompanying drawings, is a specification, like letters on the drawings representing 10 ing like parts.

My invention relates to sparking devices for internal combustion engines, more particularly to the construction of sparking plugs and induction coils therefor.

15 My invention aims generally to improve devices of this type by providing simple and effective means for increasing the capacity and efficiency of the coil and perfecting the insulation thereof and to that end comprises 20 novel features of construction and arrangement that will be best understood and appreciated by reference to the following description when taken in connection with the accompanying drawings, of a spark plug embodying one form of my invention and selected for purposes of illustration, its scope 25 being more particularly pointed out in the appended claims.

In the drawings; Figure 1, is a vertical 30 and longitudinal section taken through the axis of a spark plug, embodying a preferred form of my invention, selected for illustration herein. Fig. 2, a perspective view illustrating the manner of winding the induction coil and insulating the secondary terminals thereof; Fig. 3, a similar view of the primary coil to show the manner of carrying in one of the terminals of the secondary and the manner of winding the latter; Fig. 4, a 35 detail illustrating the method of winding and insulating the conducting convolutions of the coils from one another; Fig. 5, a perspective detail of the insulation tabs or strips, to show the method of applying the 40 same to the secondary terminal; and Fig. 6, a perspective detail illustrating the porcelain disk through which the secondary terminals are led to the sparking devices.

45 Referring to the drawings and to the particular embodiment of my invention selected for illustration therein, I show a sparking plug that is particularly, though not exclusively, adapted for use with internal combustion engines for automobiles, launches, 50 and the like.

This plug comprises a casing to receive an induction coil and suitable sparking electrodes, uniting in a single and compact structure the essential parts of a sparking device.

In the present instance, referring to Fig. 1, the induction coil comprises primary and secondary windings efficiently insulated from one another and the metallic conducting portions of the casing. The coil is provided with a core 1, preferably formed of a 60 bundle of soft iron wires, inclosed in a shell or sleeve 2 of suitable insulating material, which, as herein, is preferably somewhat longer than the core, so as to insulate the 65 ends of the latter from the windings of the 70 coil. This core receives the primary winding 3, shown in section in Fig. 1, which is 75 suitably wound thereon and comprises, in the present instance, a plurality, herein two, 80 layers of wire having the terminals 4, Fig. 75 1, led up through the top of a casing 5, with which the spark plug is provided, to suitable binding posts 6 mounted upon its outer end (the top, Fig. 1). Each of the layers of the 85 primary winding and also those of the secondary, presently described, comprise a number 90 of convolutions or strands 7, Figs. 3 and 4 of bare or uninsulated wire and intervening convolutions or strands, 8, of silk or 95 other suitable insulating material, said 95 strands being wound together, side by side around the core or upon an inner layer. By this arrangement the silk strands, which intervene between the adjacent conducting convolutions of bare or naked wire, form 100 the only insulating medium between them. The successive layers of the windings of the coils are insulated from one another by suitable insulating material, 9, herein preferably sheets of varnished fabric, paper, oil 105 silk, or the like, which are of high insulating properties. Outside of the primary winding, 3, is a layer or shell, 10, of insulating material, upon which the secondary coil is wound, said shell being similar to the 110 sheets 9, described, but preferably thicker effectually to insulate the primary and secondary windings from one another.

The secondary coil or winding, Figs. 1 and 2, comprises a plurality of layers of the relatively fine bare wire, 7, with the intermediate insulating strands 8 and the insulating sheets 9, described. The winding of this coil and the manner of carrying out and insulating its lead wires or terminals 110

11, 12, is a feature of considerable importance. As here shown, suitable tabs or strips 13, 14 of insulating material are laid lengthwise upon said terminals to insulate them from the bare or insulated wires of the secondary and from one another. While it is a matter of individual preference whether both of these terminals be directly connected to the sparking electrodes or one of them 10 grounded upon the casing which is in electrical connection with one of the electrodes, I have found the most advantageous results to be secured and provide a more efficient coil by carrying both terminals, as herein, 15 out to one and the same end of the coil for convenience in connecting them to the sparking electrodes 36, 37 (hereinafter described), provided at the same end of the plug.

20 In winding this secondary, the inner lead wire or terminal, 11, is arranged longitudinally or is laid lengthwise and received between the folds of the insulating tab or strip 13, as best represented in Figs. 3 and 5, said strip having a perforation or aperture at its folded end to permit said terminal 11 to be led therethrough to center the same within its insulating envelop.

The terminal, thus insulated, is laid longitudinally or lengthwise upon the insulating shell of the primary coil, Fig. 3, and the winding is commenced at about one fourth of an inch from the end of the insulation and that end of the coil, the top, Fig. 1, so 35 that the conducting portions of the coil are separated and insulated from this end of the coil. The last turn of this layer and the first of the next, etc., terminate at the same distance from the opposite end of the coil, 40 thereby providing the coil with insulated ends, thus protecting and insulating the bare windings inclosed between the insulating sheets 9. The strands of wire and the intervening strands of silk are wound around 45 the core or shell until one layer has been provided, when a layer of insulating material, such as that described, is wound around it with its sides or end portions extending to the ends of the shell 10. By this construction 50 the conducting portion of this layer of the winding is entirely inclosed or covered by the insulation thus provided. A plurality of layers are then wound in like manner until the desired number have been provided, each layer being insulated from those adjacent thereto and at the ends of the coil by the sheets 9.

By using uninsulated or bare wire, as described, the length of the wire employed in 60 making a coil of desired size, for instance that usually provided for spark plugs, may be made much greater than the length hitherto employed, this being apparent from the fact that the diameter of the bare wire is much less than insulated wire. This con-

struction therefore permits a greater number of layers of such wire to be used in making a coil of given size or diameter, thereby providing a spark plug coil that, under the usual working conditions, is of greater capacity or higher potential than those provided with insulated wire. 70

As hitherto constructed, induction coils that are provided with windings of bare wire have their bare terminals carried out 75 to the opposite ends of the coil and being thus widely separated, no insulation is required. In devices of this type, however, where it is desirable or necessary to bring the terminals near together, the necessity 80 for providing efficient insulation is a matter of considerable importance, more especially where they are carried out to one and the same end of the coil and also where the construction of the plug necessitates arranging 85 the terminals near together, or provides little space to receive them. The same necessity for providing an efficient insulation is apparent when the terminals are carried out at opposite ends and one is lead back, either 90 within or without the casing, to connect it to one of the sparking electrodes, which are necessarily in close relation, for without such insulation sparking and short circuiting would take place either between the terminals, as they are brought near together, or between the terminal leading from the far end of the coil and the adjacent portions of 95 the coil, the casing, or other parts of the plug. 100

In providing spark plugs or analogous devices with coils having bare windings, therefore, the insulation of the terminals, especially when they are carried out to the same end of the coil should be very efficient or high to prevent sparking or grounding. By employing suitable envelops of insulating material such, for example, as the tabs or strips herein described, for inclosing the exposed ends of the terminals and by also carrying said envelops into the body of the coil, I provide efficient means for effectually insulating these terminals, so that sparking other than that produced at the sparking electrode is eliminated. 110

While, obviously, one of the terminals of the secondary may if desired be grounded upon the casing of the plug, in the present instance, I preferably carry both terminals 11, 12, Fig. 2, of the secondary out to one and the same end of the coil for convenience in connecting them to the sparking electrodes. This arrangement is best shown in Fig. 2, wherein the last turn of the outer secondary winding, shown at 15 in the lower left hand corner of said figure, has its terminal carried through an aperture 16 in the folded end 17 of the insulating strip 14. This strip is also arranged longitudinally 120 upon the coil in a manner similar to that in 130

which the strip 13 is arranged. These folded strips respectively receive the terminals of the secondary, Fig. 2, between their folded portions, said terminals being centrally 5 and longitudinally arranged to extend between the inner surfaces of said portions so that the terminals are completely embedded in insulating material, which insulates them from all conducting portions of the coil or 10 plug. Said strips, 13, 14, may be made of any suitable insulating material though, in the present instance, I prefer to employ a flexible fabric, such as linen or silk, which is covered with varnish or oil of high insulating properties and which causes the inner 15 faces of the strips to adhere, so that the metal terminals are longitudinally secured in position between the folds of said strips. By this construction, the possibility of 20 sparking between the several strands or layers of either coil and the terminals is prevented, since the latter are completely inclosed in insulating material. The ends of these strips, shown at the right Fig. 2, and 25 at the bottom of the coil, Fig. 1, are carried out beyond the insulating ends of the coil to insulate the exposed ends of said terminals from all conducting portions at that end of the coil, as will be more fully described. 30 Any suitable means may be employed to secure the inner ends of the insulating strips 13, 14, in position upon the coil, one method being shown in Fig. 2, wherein the strip 14 is shown as secured to the last layer of the 35 secondary by strips 18 of suitable material, such as gummed or adhesive paper. The coil next receives a final layer of the insulating material, shown at 19, Fig. 2, preferably composed of the same varnished 40 fabric. Finally, the coil is immersed in a vessel containing an insulating, heat resisting, waterproof varnish or other similar medium, and preferably sterling varnish, which is allowed to soak in until the inter- 45 stices or spaces between the different convolutions of the windings and the layers of insulating material, and especially between the ends of said insulating layers at the ends of the coil, have been filled with said varnish 50 or medium. The coil is then taken out and baked or otherwise dried after which this process is repeated one or more times, finally leaving all conducting portions of the coil thoroughly coated and insulated by said medium and the separate parts of the coil 55 united into one substantially solid structure.

As thus prepared, the coil is inserted in a relatively thick removable shell or sleeve 20 of waterproof, heat resisting, and insulating material, herein mica, which together with said coil is inserted into the tubular metallic casing 5 of the plug and which is preferably of non-magnetic material. 60 As here shown, the rear end of this casing 5 is closed by insulating disks or washers 21, 22, and 23, also of mica or like material, which are held in position between the end of the coil and the inturned end, Fig. 1, of the casing. Immediately above this end of 70 the casing is a block, here shown as a disk 24 of insulating material, for example, mica, which is provided with suitable apertures alined with and to receive the primary terminals 4. This disk is provided with binding posts, 6, adapted to receive both the primary terminals and the terminals of an electric circuit (not shown) containing a battery, dynamo, or other suitable source of electromotive force and suitable vibration or other interrupting means. These posts and the block of insulating material are held in place upon the head of the casing 5 by any suitable means, here shown as screws 25, the heads, 26, of which are 75 notched to receive said terminals and are retained in the insulating disk 21. 80 As here shown, Fig. 1, the binding posts are apertured to receive the primary terminals 4, which are maintained in firm conducting contact therewith by means of removable plugs or wedges 4*, which are driven in from the outside and act to close up the apertures and thereby entirely close 85 this end of the plug and prevent the entrance of moisture. At its front end the casing is closed by a cap or head 27, Fig. 1, 90 preferably of metal having a threaded, reduced portion forming a nipple 28, adapted to be screwed into the aperture provided 95 in a wall of the engine cylinder. This casing head rests against an annular mica ring 29, in turn resting against a thick plate 30 of insulating material, herein porcelain, which with said mica constitute a suitable 100 heat resisting medium between the end of the casing and said coil. This plate is provided with a hub like or depending projecting central portion 31, fitting into a corresponding recess 32 in the adjacent face of 105 the head 27. The depending central portion of this head is provided with longitudinally tapered passages to receive tapered hollow shells or conical sleeves 33, of insulating material, preferably of mica which project 110 beyond the threaded end of the nipple 28, and at their inner ends enter suitable recesses 34, centrally located in the depending 115 projecting portion, 31, of said porcelain plate. To hold these sleeves firmly in place 120 within said head, I provide tapered plugs 35, 35*, of suitable conducting material, for example, brass and drive them into the open ends of the mica sleeves as shown in Fig. 1. Secured at and within the outer ends of 125 these metallic plugs are the sparking electrodes 36, 37, of suitable conducting material preferably German silver or platinum, the electrode 36 having a right angular arm 36* and the electrode 37 consisting of a sub- 130

stantially straight piece of wire. These plugs are driven into said sleeves to such depth that their lower ends, see Fig. 1, are above the adjacent ends of the sleeves, the 5 sparking terminals being surrounded by the heat resisting and insulating walls of said sleeves for substantially their entire length, leaving only their sparking points exposed. By this construction the metallic sparking 10 electrodes are nearly inclosed by a shell of insulating material, all the metal parts of the plug being widely separated therefrom; moreover by arranging the sleeves so that their lower ends extend below said metal 15 parts and driving the conducting plugs in beyond said ends, the possibility of a bridge of carbon deposit being formed between said electrodes or either or both of them or their plugs and the metallic portions of the nipple is eliminated. Moreover the oil that enters or collects in the open ends of the heat 20 resisting mica sleeves is maintained in a liquid state since said sleeves prevent the conduction of enough heat from the explosion chamber to their interior thus preventing the carbonization of the oil therein.

The porcelain plate, best shown in Fig. 6, is centrally provided with an aperture in approximate alignment with the central lead 30 wire or secondary terminal 11, which is led through said aperture, said recess 34 and the opening in the mica sleeve 33, to a central longitudinal aperture in the plug 35 where it is secured by means of a taper wedge 38 35 driven in from the outer end of the plug.

To provide for suitably insulating the other secondary terminal 12, the porcelain disk is provided with a laterally extending and angular rib 39, Fig. 6, suitably apertured as at 40 to receive said terminal 12. This aperture leads inward to the recess 34, which communicates with the opening in the tapered mica sleeve 33. The secondary terminal 12 is led through this aperture and 45 said mica sleeve and at its outer end is similarly secured within the metal plug 35 by a tapered plug 38^a, which maintains the terminal in electrical contact with the conducting plug 35 and its sparking terminal 37. 50 By this arrangement, the plugs within said mica sleeves effectually seal up all openings and close the plug against the entrance of moisture or gases.

An important feature of my invention relates to the thorough and efficient insulation of the secondary terminals both from the conducting portions of the casing and the adjacent conducting portions of the coils or their core. As here shown, referring to Fig. 60 2, the tabs or folded strips of insulating material 13 and 14, which extend lengthwise of and upon the inner and outer surfaces of the secondaries 11, 12, are carried out to and extend beyond the lower end of the coil (the 65 right Fig. 2), said strips being thick enough

to prevent rupture by sparking from such adjacent conducting portions of the coil as are of higher or different potential and wide enough to prevent the sparks passing between the secondary engaging faces of the 70 folds of said strips.

Referring now to Fig. 1, the fold 13^a of the insulating strip at the inner side of the terminal 13 is folded radially inward across the end of the primary, its metal core, and 75 the opposite portion of the secondary, with its end laid up against the similarly infolded fold 14^a of the insulating strip 14 of the outer secondary terminal 12. This fold 14^a, Fig. 1, underlies the fold 13^a being infolded 80 in the opposite direction, its inner end bearing upon the inner central terminal 11, the two infolded folds 13^a, 14^a together presenting a double thickness of insulating material between the conducting portions of the secondary or primary or the core which are of 85 different potential and between which a spark might pass, unless properly insulated.

As has been stated, the width of the strips is sufficient to prevent sparking laterally or 90 between or across the strips and forms an efficient insulation at the end of the coil.

The outer fold 14^b of the strip 14 extends downward and is arranged between the circumferential edge of the porcelain plate 30 95 and the insulating sleeve 20 of the casing thereby increasing the efficiency of the insulation at that point. Similarly the outer fold 13^b of the opposite strip 13 extends outward radially between the coiled ends of 100 the insulation layer of the secondary and the upper or inner face of the porcelain disk and into substantial contact with the insulating sleeve 20. As here shown, the porcelain plate flattens the ends of the strips out 105 across the adjacent face of the coil, so that the recess formed between the inner face of the insulating and heat resisting porcelain plate and the adjacent insulated ends of the coil of the secondary is partially filled with 110 a medium of high insulating properties which also forms a backing to secure the coil in place within the casing and prevent vibratory movement thereof. If desired, a 115 suitable waterproof, heat resisting and insulating cement, powder, or other like material, for example, a composition of rotten stone and shellac, the latter dissolved in alcohol, or varnish and granulated asbestos or mica may also be used to fill or partially fill 120 this recess and that at the top of the coil, to prevent displacement of the movable parts. This material, represented at 41, not only perfects the insulation of the coil but also prevents the admission of moisture and the 125 transmission of heat, which is particularly desirable when the coil is mounted upon parts of relatively high temperature as in the present instance.

While the space between the insulated 130

ends of the coil and the porcelain or mica plates may obviously be left vacant, the air therein being a good non-conductor of heat, if a filler is used, it should be composed of 5 heat resisting and non-conducting material. It will be understood by those familiar with the art that spark plugs are subjected to heat of relatively high temperature and in constructing a coil plug it is exceedingly advantageous to provide it with every possible practical feature that tends to prevent heating it, that does not otherwise impair its efficiency. To this end, the casing, the closures for its ends, the lining shells, the coil, 10 in fact, the entire construction of the plug includes novel features for maintaining the plug at a substantially uniform temperature, so that the coil may not be heated and its efficiency and durability maintained. 15 The inner face of the rib 39, referred to, extends inwardly at an angle from the center of said plate, as best shown in Fig. 6. In the position in which said porcelain plate is secured within the casing, Fig. 1, said rib 20 indents the adjacent end portions 13^a, 14^a, of said strips 13, 14, into the adjacent ends of the insulation layers 9 of the secondary thereby increasing the insulation at that point and preventing leakage or sparking 25 between the secondary terminal 12 at a point of relatively high potential and the nearest portions of the secondary, the primary, or the core, thus eliminating the possibility of short circuiting. 30 By constructing the plug and coil in this manner, I provide a device that is not only strong and durable but is compact, heat resisting and waterproof, the sparking electrodes being mounted upon the same structure with the secondary coil and directly 35 connected therewith by means of heavily insulated leads, thus avoiding loss by grounding of the secondary or lengthy secondary lead wires. Furthermore, the thick porcelain plate at the lower end of the plug, 40 provides efficient heat resisting means which, being interposed between the sparking terminals and the induction coil, prevent injury to the latter by the action of heat. 45 As will be understood by those skilled in the art, the plug and its contained coil described are adapted to be used with an exteriorly arranged and independent vibrator magnet. The construction and arrangement 50 of the plug described permits the application of a number of such plugs to the several cylinders of a multiple-cylinder engine while using a single exterior vibrator and vibrator magnet, the primary coils being 55 connected in multiple with each other and 60 in series with a main circuit containing the vibrator-magnet and source of electrical energy.

This arrangement maintains the induction coils in close proximity to the sparking

terminals thereby avoiding the use of exposed secondary terminals or lead wires and securing the practical advantage of a single vibrator for the several coils. The compactness of the plug permits its addition to 70 the engine cylinder, while occupying practically the same space or room as the ordinary spark plug.

So far as I am aware, this is the first instance in the art in which coils composed of 75 windings of bare wire, or coils provided with heavily insulated terminals have been provided for use in spark plugs, thereby eliminating the use of exposed secondary lead wires and auxiliary sparking devices. 80

One feature of my invention to which especial attention may be directed and which may be embodied in other specific coil constructions than that herein disclosed, is the complete insulation which is afforded the 85 secondary lead in passing from the coil to the sparking electrode by means of the continuous overlapping insulating elements which are compactly but efficiently arranged between the end of the coil and the electrode. 90

While in the embodiment of my invention herein disclosed, the secondary terminals of the spark coil are insulated from one another and the casing and both directly 95 connected to the sparking electrodes, my invention is not limited to such specific arrangement and it is to be understood that I contemplate applying the broad features thereof to spark plugs in which one of the 100 terminals may be indirectly connected to one of the sparking electrodes as by grounding it upon the casing, though I prefer the present construction which is much more efficient. 105

While in the particular embodiment of my invention herein selected for illustrative purposes only, I have described the same with reference to a spark plug and to a coil having windings of particular type and provided with insulating strips of fabric, it is to be understood that my invention is not limited thereto nor to the specific details of construction and arrangement, since the same is capable of modification within wide 110 limits without departing from the spirit and scope of my invention.

I claim—

1. In a device of the type described, a spark coil having a terminal carried out to 120 extend from one end thereof, means comprising flat strips of insulating material laid lengthwise upon and enveloping said terminal for inclosing and insulating the exposed end thereof from the adjacent conducting portions of said coil, and a pair of 125 sparking electrodes with one of which said terminal is connected.

2. In a device of the type described, a spark coil having a terminal carried out and 130

extending from one end thereof, flat strips of insulating material laid lengthwise upon and enveloping said terminal and also extending into the coil to cover and insulate said terminal from the adjacent conducting portions of said coil, and a pair of sparking electrodes with one of which said terminal is connected.

3. In a device of the type described, a spark coil having terminals carried out and extending from one end thereof envelops of insulating material inclosing each of said terminals for insulating the exposed ends thereof, the inner end portions of said envelope extending across the end of the coil and together providing a plurality of layers of insulating material between said terminals and the conducting portions of said coil and a pair of sparking electrodes with which said terminals are connected.

4. A spark coil provided with primary, and secondary windings, the latter having a terminal carried out and extending from one end thereof, means comprising strips of insulating material having a greater width than the diameter of said terminal and adapted to conform to the circumference of the coil without substantially increasing the diameter thereof and longitudinally arranged upon said terminal for covering and insulating it from the conducting portions of said coil, and a pair of sparking electrodes to one of which said terminal is connected.

5. A spark plug coil having sparking electrodes, a winding of bare wire, and wire terminals connected to said sparking electrodes, insulating means between adjacent convolutions of said wire, layers of insulating material between adjacent layers of said wire, a layer of insulating material about the outer layer of said wire, insulating means for protecting said wire terminals, the last-mentioned insulating means being distinct from and extending between two adjacent layers of said insulating material, and other coöperating, insulating means leading to the sparking electrodes.

6. A spark plug comprising a casing, a sparking electrode, an induction coil within said casing provided with a winding of bare wire and a wire terminal, insulating means for protecting the body of the coil to insulate the same from the bare windings thereof, and separate and distinct insulating means covering said wire terminal and leading from the sparking electrode and terminating at a point within the first-mentioned insulating means.

7. In a spark plug the combination of a casing, an induction coil within said casing provided with a winding of bare wire and a wire terminal, means for insulating the convolutions of said coil from one another, insulating means for protecting the otherwise

bare and exposed end of said terminal and also extending into the body of the coil and terminating within the insulation of the body of the coil to insulate the wire terminal from the bared metallic windings of the coil, a filler of insulating material for sealing the end of said casing adjacent said terminal, and a pair of sparking electrodes with one of which said terminal is connected.

8. A spark plug having a casing, a coil within said casing having primary and secondary windings, the latter being wound with bare wire, means for insulating the convolutions of said wire from one another, means whereby the casing may be attached to an engine cylinder, a sparking electrode, a bare wire secondary terminal leading from the attaching end of the casing and connected with said electrode, and continuously arranged but individually distinct insulating elements extending from said electrode to and terminating within and overlaid by the insulation of the body of the coil for insulating said otherwise bare terminal.

9. A spark plug having a casing, a coil within the casing having primary and secondary windings, the latter wound with bare wires and intervening separating strands of insulating material and having wire terminals, sparking electrodes carried by said casing and connected with said terminals, and protective insulation for the otherwise bare secondary terminals extending into and terminating within the insulation of the body of the coil and other coöperating, insulating means extending to the sparking electrodes to provide a continuous insulation for the terminals.

10. A spark plug comprising a casing having a head adapted to be secured to an engine cylinder, sparking electrodes carried by said head, an induction coil within said casing having windings of bare wire with means for insulating the adjacent convolutions from one another, a wire terminal carried out to the end of the coil adjacent said head and connected to one of said electrodes, and an envelop of insulating material distinct from said convolutions insulating means for inclosing and insulating the portion of the otherwise bare wire terminal intermediate said coil and said head, said envelop extending within and being inclosed and overlaid by the insulating means of the body of the coil.

11. A spark plug comprising a casing having a head adapted to be secured to an engine cylinder, sparking electrodes carried by said head, an induction coil within said casing having windings of bare wire with means for insulating the adjacent convolutions from one another and a wire terminal carried out to the end of the coil adjacent said head and connected to one of said electrodes, an envelop of insulating material

distinct from said convolutions insulating means, and inclosing and insulating the portion of the otherwise bare wire terminal intermediate said coil and said head, said envelop extending within and being inclosed and overlaid by the insulating means of the body of the coil and a filler of insulating material for insulating the end of the coil adjacent said head.

10 12. A sparking plug provided with a casing having a head provided with means for attaching it to an engine cylinder, an induction coil wound with bare wire within said casing having one of its bare wire terminals carried out to the end of said casing adjacent said head, means for insulating the convolutions of said wire from one another, a plate or disk of insulating material between said head and the adjacent end of the 20 coil, and provided with means to receive said terminal, and an envelop of insulating material distinct from said convolutions insulating means for inclosing and insulating the portion of said terminal between said 25 plate and the adjacent end of the coil, said envelop extending within and being inclosed and overlaid by the insulating means of the body of the coil.

13. A sparking plug provided with a casing having a head provided with means for attaching it to an engine cylinder, an induction coil within said casing having one of its terminals carried out to the end of said casing adjacent said head, a plate or disk of insulating material between said head and the adjacent end of the coil, and provided with means to receive said terminal, an envelop of insulating material for inclosing and insulating a portion of said terminal between said 40 plate and the adjacent end of the coil and a heat resisting filler for filling the space between said plate and said coil and enveloping said terminal.

14. A spark plug having a casing, an induction coil within said casing having its terminals carried out to one end of the coil, an insulating plate at the terminal end of said coil and provide with recesses, shells of insulating material arranged in said recesses 50 to receive said terminals, and envelops of insulating material for insulating the exposed portion thereof and the adjacent conducting portions of said coil, each of the envelops having end portions extending laterally between the end of said coil and the adjacent face of said plate.

15. In a device of the type described, an induction coil having terminals carried out and extending from one end thereof and envelops of insulating material for each of said terminals for insulating the exposed ends thereof, an inner portion of each of said envelops extending across the end of the coil and providing a double layer of insulating material between said terminals

and the conducting portions of said coil, a casing in which said coil is mounted, a plate of insulating material for closing said casing at the terminal end of said coil and provided with means to receive said terminals, 70 said plate being arranged to press the ends of said envelops against the adjacent end of the coil and supporting the latter within said casing, and sparking electrodes with which said terminals are connected. 75

16. A sparking plug for internal combustion engines comprising a casing, an induction coil arranged therein having primary and secondary windings and a secondary terminal carried out to one end of said casing, a plate for closing the end of the casing adjacent said terminal and provided with means to receive said terminal, a head exterior to said plate and secured to said casing and provided with means to adapt the same to be attached to an explosion engine, an envelop of insulating material for said terminal, means for insulating the exposed portion of said terminal between the end of the coil and the inner face of said plate and 90 to prevent sparking between said terminal and the adjacent conducting elements of said coil or said plug, an insulating shell carried by said head, a metallic conducting plug carried thereby, means for securing 95 said terminal thereto, and a sparking electrode carried by said conducting plug.

17. A spark plug comprising a casing, a coil therein provided with a plurality of convolutions of bare wire, intervening convolutions of insulating material and an outer layer of insulating material, and a terminal also of wire provided with an insulating envelop distinct from said material to prevent 100 sparking between said terminal and the adjacent wire conducting portions of said coil or said casing, said envelop commencing within the body of the coil intermediate said outer layer and the adjacent layer of the wire and extending beyond the end of the 110 coil to insulate said terminal from the adjacent conducting portions at the end of said coil, and sparking electrodes to one of which said terminal is connected. 105

18. A spark plug provided with a casing, 115 a head therefor, a coil within said casing, an insulating shell mounted on and projecting outwardly beyond said head, and a sparking electrode having its inner end secured at a point within and inwardly beyond the outer 120 end of said shell, the latter projecting from said head and enveloping said electrode beyond the point where it is secured to a point adjacent the sparking terminal thereof.

19. A spark plug having a casing, an induction coil therein, the latter provided with a secondary wound with bare wire, and wire terminals, a sparking electrode to which one of said terminal electrodes is connected, an insulating body at the terminal end of said 130

secondary winding, through which insulating body the said secondary terminal passes, and an insulating envelop inclosing an otherwise bare wire terminal and extending 5 into and terminating within the body of the coil and filling a portion of the space between the said body and the coil.

20. A spark plug having an induction coil, an insulating plate at one end thereof, 10 insulating material between said plate and said coil, a terminal passing from said coil

through said plate, said plate having a raised portion acting to press against said insulating material.

In testimony whereof, I have signed my 15 name to this specification, in the presence of two subscribing witnesses.

ISRAEL C. ORSWELL.

Witnesses:

ROBERT H. KAMMLER,
SIDNEY F. SMITH.
